ABSTRACT: A collapsible stand for supporting signs and the like above the ground includes a pair of spaced upright posts for receiving the sign. A tie bar joins the posts and is hinged to the lower ends of the posts. A plurality of elongated feet hinged to the lower ends of the posts lie normal to the tie bar. The tie bar and feet abut the ground for retaining the stand in position, while at the same time, maintaining the posts upright.

COLLAPSIBLE SIGN STAND

BACKGROUND OF THE INVENTION

1. Field of the Invention

The present invention relates to holding supports or stands.

2. Description of the Prior Art

The present invention relates to collapsible stands and more particularly to stands suitable for use in supporting and displaying warning signs and the like. Such signs are necessary for reasons of safety, or pursuant to legal requirements, in areas where work is being done on or adjacent roadways and thoroughfares to warn passing motorists of the presence of equipment and workmen and to provide protection to the latter.

It will be appreciated that the warning signs and their stands are transported to and from the work site in the same vehicles as the workmen and their equipment so that a premium is placed on lightweight, compact stands which do not unduly displace men and equipment from the work vehicle. For this reason, warning sign stands have usually been constructed so that they may be collapsed for transportation and storage. Such collapsible signs have generally comprised a tripod supporting a mast on which the warning sign is mounted for display.

However, as the speed of motor traffic has increased, it has become necessary to increase the size of the signs in order to provide adequate, informative warnings to the passing motorists. It has also become necessary to raise the height of the sign off the ground to a higher level to insure that the motorist's attention is drawn to the sign. This need for larger, higher signs has placed additional burdens on the stands used to support such signs. In addition to the increased weight of the sign, the stand is subject to greater wind loads both due to the greater area of the sign and the greater moment arm through which the wind force acts. The wind generated by passing vehicles causes repetitive impulse forces on the stand.

Under such conditions, tipping or displacement of tripod sign stands may occur which eliminates or lessens their warning function. This dislodgement of the stand is attributable to the small surface area of the tripod in contact with the ground, this surface area being only the bottom surfaces of the three legs of the tripod. Additionally, the inherently rigid structure of the tripod necessary to retain the mast upright prevents the stand from readily absorbing momentarily excessive wind loads thereby avoiding dislodgement.

The wind forces, or the resulting displacement or tipping, have often caused damage to, or destruction of, tripod sign stands. The tendency of tripod sign stands to tip is often increased if the stand is used on uneven ground since the configuration of the base must be altered to place the mast upright.

While conventional sign stands have been strengthened to resist increased loading, this has been at the expense of compactness and weight so that the sign stands have come to take up excessive space in the truck and to be heavy and bulky during handling and erection.

SUMMARY OF THE INVENTION

It is, therefore, the object of the present invention to provide a sign stand which is lightweight and compact, while at the same time is capable of supporting large signs and of resisting, without dislodgement, the wind loads exerted on the sign.

It is a feature of the present invention to provide a sign stand which provides a large surface area in contact with the ground thereby to resist displacement or tipping of the stand.

An additional feature of the present invention is the provision of a sign stand which has a limited amount of resiliency or elasticity between the members so as to permit the stand to absorb momentarily excessive wind loads.

The stand may be collapsed into a small bundle for storage and transport and may be used on uneven ground with little or no loss of efficiency.

Briefly, the present invention provides a collapsible sign stand having a pair of sign supporting posts. The lower ends of the posts abut the ground and are joined by a tie bar which lies on the ground and forms the posts into a unitary structure.

5 This structure is held in the upright position by pairs of feet lying on the ground normal to the tie bar and joined to the lower ends of the upright posts. The posts are sized and jointed and the tie bars and feet sized and hinged so that the stand 10 may be collapsed into a compact bundle for storage and transport. The joints or hinges between the posts, tie bar, and feet permit limited movement between the elements to provide resiliency to the stand.

15 Other objects and features of the present invention will become apparent or be noted in the following drawing and description of the preferred embodiment.

BRIEF DESCRIPTION OF THE DRAWING

FIG. 1 is a perspective view of the sign stand of the present 20 invention in its fully erected position;

FIG. 2 is a partial side view of the sign stand of the present invention with portions thereof cut away to reveal details of the upright posts of the stand, alternative positions of the post being shown by dotted lines;

25 FIG. 3 is a partial front view of the sign stand of the present invention with portions thereof cut away to reveal details of the hinge mounting of the tie bar and feet of the sign stand, alternative positions of these elements being shown by dotted lines; and

30 FIGS. 4 through 7 are perspective views showing the erection of the sign stand of the present invention, FIG. 4 showing the sign stand in a collapsed position suitable for storage and transportation, FIGS. 5 and 6 showing intermediate steps in the erection of the sign stand, and FIG. 7 showing the terminal step and the completely erected sign stand without the sign.

DESCRIPTION OF THE PREFERRED EMBODIMENT

40 A collapsible sign stand 10 of the present invention is shown in the erected position of FIG. 1 as displaying warning sign 12. Stand 10 includes a pair of spaced, vertical posts or standards 14 and 16 to which sign 12 may be removably attached as by brackets 18.

45 As shown in FIGS. 1 and 2, the lower portion 20 of posts 14 and 16 may comprise a channel member which is over half as long as the completely erected height of posts 14 and 16. The upper portion 22, which may be tubular in form, is pivotally mounted in lower portion 20 so that it may be swung upwardly, as shown by the arrow in FIG. 2, during erection of sign stand 10.

50 To form the hinge or pivot between lower portion 20 and upper portion 22 in posts 14 and 16, a pin 24 is inserted through the upper ends of the extending flanges of the channels forming lower portions 20. Each of the lower ends of upper portions 22, when the upper portions are in the erected position, as shown in FIG. 2, are provided with a slot 26, through which passes pin 24. Upper portion 22 is retained in the erected position by lowering the upper portion 22 into the channel of lower portion 20 so that pin 24 moves to the upper terminus of slot 26 and the lower end of upper portion 22 abuts the web of lower portion 20. In this manner, upper portion 22 is simply, but effectively held in the erect position on lower portion 20.

55 The distance between the lower terminus of slot 26 and the end of upper portion 22, when upper portion 22 is in the erected position, is sized to permit the end of upper portion 22 to clear the web of the channel of lower portion 20 when upper portion 22 is raised and pin 24 is in the lower terminus of slot 26, thereby to permit upper portion 22 to be pivoted about the pin to the collapsed position shown in FIG. 2 in dotted lines. The length of upper portion 22 may be such as to permit upper portion 22 to lie within the lower channel of lower portion 20. The upper end of upper portion 22 may be

provided with tubular holders 28 for flags 30 which assist in drawing the motorist's attention to the sign. With tubular holders 28 attached to upper portions 22, the ends of upper portions 22 lie outside the channels of lower portions 20 when in the collapsed position, as shown in FIG. 2.

It will be apparent from the foregoing that posts 14 and 16 provide a rigid structure capable of supporting sign 12 against the various forces applied thereto while at the same time providing a structure which compactly collapses for storage and transport.

Posts 14 and 16 are joined by tie bar 32 to form a unitary sign supporting structure. A bracket 34 comprised of a short piece of channel, similar to that used for lower portions 20, is affixed to the lower ends of lower portions 20 as by welding. Bracket 34 is mounted perpendicular to lower portion 20 so that the web of the channel is in contact with the ground when sign stand 10 is in the erected position as shown in FIGS. 1 and 3. The channel opens upwardly when the sign stand is viewed as in FIGS. 1 and 3. A pin is inserted between the flanges of bracket 34.

Tie bar 32, which may be tubular in cross-sectional configuration, contains a slot 38 in each end thereof through which passes pin 36 to form a hinge and maintain tie bar 32 integral with posts 14 and 16. The inner terminus of slot 38, that is, the end adjacent post 14 or 16, is positioned in the end of tie bar 32 in a manner similar to the positioning of slots 26 in upper portions 22 so that the end of the tie bar clears the web of bracket 34 to allow the tie bar to pivot with respect to bracket to the position shown by the dotted lines and arrows in FIG. 3. In the position shown by the dotted lines in FIG. 3, tie bar 32 lies approximately parallel to the adjacent post 14 or 16.

To retain or lock tie bar 32 in the lowered position, in which it forms an extension of bracket 34, and is in contact with the ground over substantially all of its length, a spring 40 is positioned inside tie bar 32. One end of spring 40 is affixed to pin 36 while the other end is affixed to pin 42 extending through tubular tie bar 32. Spring 40 urges tie bar 32 toward the adjacent post 14 or 16 and pin 36 and into the outer terminus of slot 38 so as to prevent tie bar 32 from pivoting about pin 36 due to the contact of the end of tie bar 32 with the web of bracket 34.

When in the lowered position, tie bar 32 is approximately perpendicular to posts 14 and 16 and the lower surface of the tie bar parallel to the web of bracket 34. In order to facilitate the pivoting of tie bar 32, a slight clearance may be left between tie bar 32 and the web of bracket 34 by the positioning and sizing of slot 38 and pin 36. This permits limited, rocking relative movement between tie bar 32 and posts 14 and 16 which provides the aforementioned resiliency to the structure. Spring 40, of course, continually urges the members into a position of perpendicularity.

A pair of opposed feet 44 are mounted on the lower end of each of lower portions 20 of posts 14 and 16. Feet 44 are perpendicular to posts 14 and 16 and to tie bar 32 and contact the ground on which the sign stand is placed. The mounting of feet 44 on posts 14 and 16 is accomplished in the same manner as tie bar 32 through the use of additional brackets 34, pins 36, slots 38, springs 40, and pins 42.

The length of the tie bar is slightly in excess of the length of feet 44 to facilitate the collapsing of sign stand 10.

The erection of sign stand 10 may be seen by reference to FIGS. 4 through 7. FIG. 4 shows the sign stand in the fully collapsed condition in which posts 14 and 16 are folded and tie bar 32 and feet 44 lie generally parallel and closely adjacent the posts. The location of feet 44 in the collapsed condition is facilitated by the increased length of tie bar 32 with respect to feet 44, as the length of tie bar 32 determines the height of collapsed stand 10. As this height is greater than the length of feet 44, the latter may be neatly folded along posts 14 and 16. The stand is retained in the collapsed position for storage or transport by strap 50 which encircles the collapsed stand and is fastened to post 14.

To commence the erection of sign stand 10, strap 50 is released. Tie bar 32 is pivoted downwardly about the hinge at the lower end of post 14 carrying with it post 16 joined to the other end of the tie bar, as shown in FIG. 5. Spring 40 forces the end of tie bar 32 affixed to post 14 against the post to lock the tie bar and post against further movement.

Post 16 is then swung upwardly as shown in FIG. 6 to erect the other post. Spring 40 forces the end of tie bar 32 affixed to post 16 against the post to lock the tie bar and post against further movement. Either prior to, or after, erecting post 16, feet 44 may be swung down, also as shown in FIG. 6 to retain posts 14 and 16 of sign stand 10 in the upright position. Lastly, upper portions 22 are raised on lower portions 20, as shown in FIG. 7 to complete the erection of sign stand 10.

I claim:

1. A collapsible stand for supporting signs and the like above the ground comprising:

a pair of spaced upright posts having lower ends abuttable with the ground and upper ends for receiving the sign; a tie bar joining said posts to form a sign supporting structure, said tie bar being coupled to the lower ends of said posts through hinges having a locked position for retaining said posts perpendicular to said tie bar and a hinging position for permitting said tie bar and posts to be swung together, said tie bar being abuttable with the ground; and a plurality of elongated feet coupled to the lower ends of said posts normal to said tie bar, said feet being coupled through hinges manipulatable between a locked position for retaining the posts perpendicular to the feet and a hinging position for permitting said posts and feet to be swung together, said feet being abuttable with the ground for maintaining said sign supporting structure upright.

2. The collapsible stand of claim 1 wherein said hinges are so constructed as to permit limited movement of said posts with respect to said tie bar and feet when in the locked position.

3. The collapsible stand of claim 2 wherein said hinges include means urging said posts into the perpendicular position with respect to said tie bar and feet.

4. The collapsible stand of claim 3 wherein said tie bar and feet comprise tubular members and each of said hinges includes a channel member mounted on said post at right angles thereto, said channel having a pair of spaced flanges separated by a web for receiving an end portion of said tubular members between the flanges, the end portion of said tubular members containing a slot having an inner terminus adjacent said post and an outer terminus, said slot receiving a pin extending between the flanges of said channel for pivoting said tubular member in said channel, the spacing of the inner terminus of said slot from the end of said tubular member being such as to allow the end of the tubular member to clear the web of the channel during pivoting, and spring means for urging said pin into the outer terminus of said slot and said post into the perpendicular position.

5. The collapsible stand of claim 1 wherein said upright posts are comprised of a lower portion hinged to said tie bar and feet and an upper portion pivotally mounted on said lower portion for movement between a collapsed position and an erected position, the length of said upper portion being such as to permit said portion to lie along said lower portion when the post is in the collapsed position.

6. The collapsible stand of claim 5 wherein said lower portion of said upright posts comprises a channel member having a pair of spaced flanges separated by a web and said upper portion has an end part insertable between the flanges of said lower portion, the end part of said upper portion containing a slot having a first terminus adjacent the end of said upper portion and a second terminus, said slot receiving a pin extending between the flanges of said channel for pivoting said upper member in said channel, the spacing of the first terminus of said slot from the end of said upper portion being such as to allow the end of the upper portion to clear the web of the channel during pivoting, said pin being slidable into the

second terminus of said slot to retain the upper portion of the post in the upright position

7. The collapsible stand of claim 1 wherein the length of

said tie bar is greater than the length of said elongated feet to facilitate collapsing of said stand.
